UNITED STATES PATENT OFFICE

168,418

AUTOMOBILE HEADLIGHT VISOR

David Pattis, Chicago, Ill.

Application May 10, 1952, Serial No. 19,675

Term of patent 7 years

(Cl. D48—32)

To all whom it may concern:

Be it known that I, David Pattis, a citizen of the United States, residing at Chicago, in the county of Cook and State of Illinois, have invented a new and original and ornamental Design for an Automobile Headlight Visor, of which the following is a specification, reference being made to the accompanying drawing, forming a part thereof.

In the drawing;

Fig. 1 is a front elevational view of an automobile headlight visor embodying my new design, as seen from the left hand side in Figure 3;

Fig. 2 is a rear elevational view as seen from the right hand side in Figure 3;

Fig. 3 is a side elevational view of the same; and

Fig. 4 is a top plan view thereof.

I claim:

The ornamental design for an automobile headlight visor, substantially as shown.

DAVID PATTIS.
